(57) **CLAIM**

The ornamental design for an adhesive body support, as shown and described.

DESCRIPTION

FIG. 1 is a top and side perspective view of an adhesive body support.

FIG. 2 is a top elevational view of an adhesive body support.

FIG. 3 is an elevational view of one end of an adhesive body support.

FIG. 4 is a side elevational view of an adhesive body support; and,

FIG. 5 is a bottom elevational view of an adhesive body support.

The broken lines illustrate portions of the adhesive body support which form no part of the claimed design.
